UNITED STATES PATENT OFFICE.

FRANKLIN J. PERKINS, OF WOBURN, AND FREDERIC A. PARKHURST, OF PEABODY, MASSACHUSETTS.

APPARATUS FOR APPLYING LIQUID DRESSING TO LEATHER.

SPECIFICATION forming part of Letters Patent No. 663,665, dated December 11, 1900.

Application filed December 11, 1899. Serial No. 739,933. (No model.)

To all whom it may concern:

Be it known that we, FRANKLIN J. PERKINS, residing at Woburn, county of Middlesex, and FREDERIC A. PARKHURST, residing at Peabody, county of Essex, State of Massachusetts, citizens of the United States, have invented an Improvement in Apparatus for Applying Liquid Dressing to Leather, &c., of which the following description, in connection with the accompanying drawings, is a specification, like characters on the drawings representing like parts.

This invention has for its object the production of novel means for applying liquid dressing to leather or hides and skins of any desired shape or size, the term "dressing" including for the purposes of our invention liquid blacking or other liquid coloring-matter or liquid of any character with which it is desired to impregnate the leather to a greater or less extent. So far as we are aware, such dressing, coloring, or blacking of leather has been accomplished either by hand labor entirely or by means of a rotatable brush or spreader to which the liquid is fed and which applies the liquid to the work. The hand method produces good results of uniform character, but it is very slow, as the dressing is usually applied with a woolen swab rubbed over the work, while the brush apparatus produces uneven work which has to be gone over by hand, as the stock is apt to be marked, scratched, or otherwise injured when the brush becomes dirty. The brush also acts to plait the skin on the flanks and neck and doubles the skin over as its end passes under the brush, thereby abrading the under side of the skin. It is also a practical impossibility to keep the brush clean enough to prevent streaky scratching operation thereof.

In practicing our invention we sustain the work on a suitable support and direct the dressing thereupon in the form, preferably, of a fine spray by or through pneumatic pressure, relative movement of the work-support and spraying device providing for the subjection of the work to an even application of the liquid in a very rapid, uniform, and perfect manner. The liquid is directed against the grain side of the work to fill the pores thereof, the pressure with which the liquid

is driven into the work determining in large measure the depth to which it penetrates.

We prefer to subject the work to an airblast after the liquid dressing has been applied to blow off or dissipate any drops which may have formed and also to assist in drying the work after treatment.

Figure 1 is a rear elevation, centrally broken out, of an apparatus embodying one form of our invention and showing a suitable counter-shaft for actuating the same. Fig. 2 is a left-hand end elevation of the apparatus shown in Fig. 1. Fig. 3 is an enlarged sectional view of one of the spraying devices, to be described. Fig. 4 is a perspective view of the receptacle for receiving any overflow or waste liquid. Fig. 4^a is a cross-sectional view of the said receptacle; and Fig. 5 is a detail plan view, enlarged, of a guideway and adjusting device, to be described.

We have herein shown the apparatus as mounted on a suitable bed or base plate A, on which standards or end pieces A' are erected, having suitable bearings A² for a driving-shaft B, provided with usual fast and loose pulleys B' B², which are connected by a belt (not shown) with a pulley C on a suitable counter-shaft C^X, herein shown as located above the machine and supported by hangers C'. The shaft B has fast upon it a gear B³, in mesh with another gear D³ on one of the journals of a preferably-hollow drum D, rotatively mounted in bearings A³ on the end frames, said drum having preferably end flanges or ribs d. (See Fig. 1.)

Referring to Figs. 2 and 5, each end frame has at the front of the machine a flat guideway A⁴, on which a sliding bearing A⁵ is mounted, each bearing having a depending threaded lug a⁵ (see dotted lines, Fig. 2) entering a slot 100 in the guideway, to be engaged by an adjusting-screw a⁴, provided with a hand-wheel a³ or other device by which it can be readily turned to thereby move the bearing A⁵ in or out on its guideway, the screw being held from longitudinal movement. The bearings A⁵ support the journals D² of a second and also preferably hollow drum D', having end flanges d', and over the two drums is passed an endless apron or work-support D^X, preferably of fine wire-cloth or

other suitable reticulated fabric kept in the requisite taut condition by means of the adjustably-mounted drum D', the work-support being moved longitudinally by rotation of the drum D and being maintained in place laterally by the drum-flanges referred to.

The apron or work-support is preferably wide enough for any hide, skin, or piece of leather which may be had, and when smaller pieces are being treated the reticular nature of the work-support permits the dressing material to pass through it beyond the edges of the work, thus avoiding loading up of the work-support with the dressing, &c.

15 The end frames A' of the apparatus support a suitable waste or overflow receptacle D⁸, interposed between the upper and lower runs of the work-support (see Fig. 2) and having a transverse opening d⁸ in its top (see Fig. 4) below the distributing means for the dressing, to be described. An inclined shelf d⁹ within the opening receives the liquid which passes through the work-support and conducts it to the interior of the receptacle D⁸, and across the rear end of the latter is a second similar opening d¹⁰ and an upturned lip or flange d¹² for a purpose to be described. We prefer also to inclose the frame below the lower run of the work-support by a hood H, (see Fig. 2,) in which a suitable rotary brush H^X is mounted on journals h^X, that one at the far side of the machine viewing Fig. 2 having a sheave h² thereon (see dotted lines) and driven by a belt h³, passed around a sheave b²⁰, fast on the shaft B, the brush engaging the face of and cleaning the work-support as it travels along.

Above the work-support a transverse preferably closed chamber M is mounted on the side frames to contain the liquid dressing, color, or other material which is to be applied to the work, a main supply-pipe M' being supported at the top and front of the chamber and communicating with the contents of the latter by feeders M², three being shown in Fig. 1, the feeders preferably extending down to near the bottom of the chamber. (See dotted lines, Fig. 2.) Each feeder is controlled by a suitable valve, the handle m^X being connected with a cross-rod m, by which the valves can be regulated easily from the side of the apparatus.

Referring now to Figs. 2 and 3, a series of atomizers M³ are connected with the supply-pipe M' by depending ducts m³, the lower or delivery end of each duct having preferably divergent outlets m⁴, Fig. 3, and extending into a discharge-nozzle m⁵, having an outlet-orifice m⁶ and forming a part of the atomizer. The several atomizers are connected one with the other by short couplings or pipes m⁷, screwed into or otherwise secured to a chambered portion m⁸ of the atomizers, and thus communicating directly with the interior of the latter. At one side of the apparatus the couplings or pipes m⁷ are connected with a

head M⁴, into which a pipe m⁹ leads from a reservoir M⁵, held in suitable seats A¹⁰ on the base of the frame. An air-pump P of any suitable construction has its outlet-ports connected with the reservoir, the latter being thus supplied with air under desired pressure, the pump piston-rod P' being operated, as herein shown, by a pitman P², driven from the counter-shaft C^X, the mounting of the pump on the apparatus being of no importance, however. The passage of air to the head M⁴ is governed by a valve M⁸, as shown in Fig. 1.

The operation of the apparatus will be obvious from the foregoing description, the air under pressure passing through the orifices m⁶ of the nozzles m⁵ and acting to create a partial vacuum within the atomizers, whereby the liquid dressing is drawn from the supply-chamber M through the outlets m⁴ and is discharged in the form of a fine spray upon the work as the latter rests on the support D^X. By varying the air-pressure the blast can be made to drive the dressing more or less deeply into the work, according to the degree of impregnation desired, and the quantity of liquid distributed is regulated by means of valves of the feeders M². An exceedingly uniform distribution of the dressing or other liquid to be applied to the work is thus effected in a very rapid and economical manner, the work passing under the distributing or atomizing nozzles as the work-support D^X travels along beneath them.

We prefer to direct an air-blast upon the work after it has received the dressing or other liquid material to blow off drops should any have collected, and also to partly dry the work, and with this object in view we have arranged a series of air-nozzles N at the back of the chamber M, (shown clearly in Fig. 1,) the nozzles being very similar to the atomizers M³, said nozzles having outlet-orifices n^X (see Fig. 2) and being connected by short couplings n, a length of piping n² connecting the series of nozzles with the air-distributing head M⁴. A cap n²⁰ closes the endmost nozzle M farthest from the head M⁴, and a similar cap m²⁰ closes the similarly-located atomizer M³. The lip d¹² on the end of the receptacle D⁸ directs the air-blast down into the opening d¹⁰ through such portion of the work-support D^X as is left exposed by the leather or other work thereupon. It will be obvious as the air-blast is downward and the work-support perforated or foraminous that the skin or other piece of work will be pressed tightly upon the support, so that there is no chance for the work to be raised up or folded over, resulting in the application of the dressing on the wrong side of the work and producing an unsightly job. The air-blast furthermore operates to maintain the work spread out smoothly without wrinkling while the liquid is being applied thereto.

It will be manifest that so long as the work

support is foraminous or perforated the particular construction thereof is not restricted to the device herein shown.

Our invention is not restricted to the precise construction and arrangement herein shown, as we have shown one practical embodiment of our invention without attempting to show the various modifications thereof which could be made without departing from the spirit and scope of the invention.

Having fully described our invention, what we claim, and desire to secure by Letters Patent, is—

1. In an apparatus of the class described, a foraminous work-support, and means to direct upon the work liquid dressing or the like under fluid-pressure while the work is sustained by said support.

2. In an apparatus of the class described, a foraminous work-support, means to direct upon the work liquid dressing under fluid-pressure, and means to effect relative movement of the work-support and said dressing-directing means.

3. In an apparatus of the class described, a receptacle for liquid dressing or the like, a main supply-pipe connected therewith, a series of atomizers in communication with said pipe, and means to discharge the liquid from the atomizers under pneumatic pressure.

4. In an apparatus of the class described, a receptacle for liquid dressing, or the like, a plurality of atomizers having liquid-outlets connected therewith, said atomizers having their discharge-nozzles inclosing the said outlets, and means to direct air under pressure into the atomizers, to suck the liquid dressing thereinto and discharge the same in spray.

5. In an apparatus of the class described, a foraminous traveling and horizontally - extended work-support, and means located above the same to direct liquid dressing under fluid-pressure upon the work sustained by the support.

6. In an apparatus of the class described, an endless foraminous, traveling work-support, means to move it longitudinally to feed the work, and a series of atomizing devices to spray liquid dressing or the like under fluid-pressure upon the work while the latter is sustained throughout its extent by said support.

7. In an apparatus of the class described, an endless foraminous, horizontally - arranged traveling work-support, means to move it longitudinally to feed the work, a waste-receptacle beneath the upper run of the work-sup-

port, and means located over said receptacle and above the upper run of the work-support to spray liquid dressing under pressure upon the work, the dressing passing through the 60 uncovered portion of the work-support into said receptacle.

8. In an apparatus of the class described, a traveling work-support to feed the work, means to spray liquid dressing upon the work, 6; and independent means to direct an air-blast upon the work after the dressing has been applied thereto.

9. In an apparatus of the class described, a foraminous traveling work-support, a rotatable brush to engage the face of and clean 70 said work-support, and means to atomize liquid dressing or the like and direct it upon the work by fluid-pressure.

10. In an apparatus of the class described, 75 two rotatable drums, means to positively rotate one of them, a flexible, foraminous work-support carried by the drums, and means to adjust one of the latter, to regulate the tension of the work-support.

11. In an apparatus of the class described, two rotatable drums, means to positively rotate one of them, a flexible, foraminous work-support carried by the drums, and a rotatable brush to engage and clean the face of the 85 work-support as it is moved by rotation of the drums.

12. In an apparatus of the class described, a foraminous traveling work-support, an adjacent receptacle for liquid dressing or the 90 like, a series of atomizers, a supply-pipe connected therewith and provided with feeders extended into said receptacle, controlling-valves for the feeders, and means to introduce air under pressure into the atomizers, to thereby discharge the dressing therefrom as spray 95 upon the work.

13. In an apparatus of the class described, a work-support, a receptacle for liquid dressing or the like, a plurality of discharge-outlets 100 adjacent the work-support, and means to discharge the dressing from said outlets under fluid-pressure.

In testimony whereof we have signed our names to this specification in the presence of 105 two subscribing witnesses.
